UNITED STATES PATENT OFFICE.

GEORGE A. KRICHBAUM, OF YOUNGSTOWN, OHIO.

PAINTER'S STRIPING-INSTRUMENT.

SPECIFICATION forming part of Letters Patent No. 355,402, dated January 4, 1887.

Application filed January 7, 1886. Serial No. 187,929. (Model.)

To all whom it may concern:

Be it known that I, GEORGE A. KRICHBAUM, a citizen of the United States, residing at Youngstown, in the county of Mahoning and State of Ohio, have invented certain new and useful Improvements in Painters' Instruments, to be known as a "Striping Instrument;" and I do hereby declare the following to be a full, clear, and exact description of my invention, such as will enable others skilled in the art to which it appertains to make and use the same, reference being had to the accompanying drawings, which form part of this specification.

15 The object of my invention is to provide for the use of painters, sign-writers, package-markers, and others a convenient instrument which incases the paint, rendering it cleanly and always ready for use, and from which the paint is expelled with an even distribution and with variations in intensity of color, as required, making uniform plain or shaded lines of any size, so that with less skill and labor than now demanded greater accuracy 20 and rapidity in the practice of the arts indicated is secured. I accomplish this object by the mechanism hereinafter described, and illustrated in the drawings, which are read with the right margin downward, and in which—

25 Figure 1 is a longitudinal view of my instrument complete. Fig. 2 is a similar view of the paint-tube *c*. Fig. 3 is a view of the feeder-case *e*, the distributor *f*, and the stopper *g*, grouped in the relative positions in which they are brought together when the feeder is formed. Fig. 4 is a side view of the revolving spool *h*, and the figure to the right is an end view of the same. Fig. 5 is a view of *h* filled with paint-holding material, constituting a paint-roller for marking plain lines, as shown immediately above. Fig. 6 is a view of *h'*, which is a paint-roller of globular form for marking shaded lines, as shown immediately above; and Fig. 7 is a longitudinal view 40 of the connector *i*.

The tube *a* is of tin or other suitable material, preferably smaller at the right or upper end, which is rimmed with a shoulder and covered by a cap turning upon a pivot that 45 penetrates it near the edge from the shoulder of *a*, and is fastened by a downward-projecting spring on its periphery opposite the pivot,

which catches in a notch in the rim of *a*. A hinged cap, with any manner of fastening or any other means of cover, may be used; but in 55 any form the cover when closed must be hermetically tight. The lower end of *a* is preferably funnel-shaped, and is permanently covered, except a small central aperture, which is threaded so as to receive the end of *i*, which 60 is a small cylinder threaded upon its outer surface.

The paint-tube *c*, made as is *a*, except reversed in the relative sizes of the ends, has at both terminations greatly-reduced diameters, 65 forming shoulders, the small ends being threaded upon their outer surfaces as a means of attachment to the contiguous parts.

The connector *i* is a casting of suitable size for the purpose of holding *a* and *c* in line rigidly, and is a short rod bifurcated at each end, preferably in part circular form, to accommodate the valve *v'* and holding between the separated parts short horizontal cylinders, the upper of which is threaded upon its outer surface, as already stated, for a means of attachment to *a*, and the lower of which is threaded upon its inner surface for a means of attachment with *c*. On the lower end of the upper cylinder appears the sucker-valve *v'*, and within 70 the lower cylinder, working against a shoulder above it, is placed the sucker-valve *v*, so that, the two valves opening in different directions, one closes when the other opens, and vice versa. Over *i* is drawn the hollow rubber 75 ball *b*, which, with openings at its poles fitting snugly around the cylinders at the ends of *i*, is identical with the similar part of a common syringe, and for a similar purpose. To guard *b* against abrasion by equalizing the pressure 80 thereon, I place upon opposite sides the guards *d d*, which are of any proper material, shaped like the bowls of spoons, and are connected by straps to hold them in place.

The feeder at the lower end of the instrument consists of the case *e*, which is a rectangular box without cover or bottom, having downward-projecting ears from two opposite sides to afford bearings for the paint-rollers, and provided upon its interior with annular shoulders upon which *f* rests supported near its edges. The distributor *f* is a flat rectangle of 85 rubber or leather to fit into *e*, resting upon shoulders therein, as stated, and perforated 90

with minute holes, so as to evenly distribute the paint upon the paint-roller beneath. The stopper *g* is a cube having a horizontal opening as large at its lower end as the space between the shoulders upon which *f* rests, and greatly diminished at its upper end, where it is threaded to receive the lower point of *c*. This part fits into *e*, and is held in place by a set-screw. The parts *e* and *g* are castings.

10 The spool *h*, the wheels of which are notched around their peripheries to prevent slipping, is filled with a paint-holding substance—that used by printers being preferred—thus forming a paint-roller, the surface of which touches *f*, and is flat for marking plain lines, and globular, as shown at *h'*, for marking shaded lines.

15 The globular paint-roller must be elastic to do the work intended; and I therefore make it by inclosing the spool in a rubber ball, which is coated with the paint-carrying material. Spools of various lengths are provided, so as to make lines of any size, the spools being readily changed by means of the elasticity of the ears of *e*.

20 25 The size of the instrument and of its several parts may be as desired. I find, however, that an instrument ten inches in length, with a sufficient capacity of *a* to hold a plentiful supply of paint, is the most convenient.

25 30 The manner in which my striping instrument operates will be readily comprehended. The tube *a* is supplied with paint made sufficiently liquid to flow readily and is closed. The operator holds the instrument with the hand clasping *d d*. A compression of *b* closes

the upper and opens the lower valve, forcing paint down through *c* into the feeder, from which it is evenly distributed over the surface of the roller, which marks the line. The greater the compression, the more dense the color of the line. When compression of *d* ceases, the lower valve closes and the upper valve opens again, filling *b* with paint. Thus does my striping-instrument fully accomplish the purpose stated in the early part of this specification.

40 45 What I claim as my invention, and desire to secure by Letters Patent, is—

1. A striping-instrument consisting of the tubes *a* and *c*, the connector *i*, having the valves *v* and *v'*, the rubber ball *b*, the guards *d d*, the feeder composed of the case *e*, the distributor *f*, and the stopper *g*, and the paint-roller *h*, substantially as described in the foregoing specification, and for the purpose therein expressed.

50 55 60 65 2. A striping-instrument consisting of the tubes *a* and *c*, the connector *i*, having the valves *v* and *v'*, the rubber ball *b*, the guards *d d*, the feeder composed of the case *e*, the distributor *f*, and the stopper *g*, and the globular paint-roller *h'*, substantially as described in the foregoing specification, and for the purpose therein expressed.

In testimony whereof I hereunto affix my signature in the presence of two witnesses.

GEORGE A. KRICHBAUM.
